UNITED STATES PATENT OFFICE.

COROL R. BAKER, OF KNOXVILLE, TENNESSEE, ASSIGNOR TO EDWARD L. FRANTZ,
TRUSTEE, OF CLEVELAND, OHIO.

AIR-COOLED ENGINE.

1,317,750.

Specification of Letters Patent.

Patented Oct. 7, 1919.

Application filed August 5, 1918. Serial No. 248,374.

To all whom it may concern:

Be it known that I, COROL R. BAKER, a citizen of the United States, residing at Knoxville, in the county of Knox and State 5 of Tennessee, formerly of Akron, Summit county, Ohio, have invented certain new and useful Improvements in Air-Cooled Engines, of which the following is a specification.

This invention relates to means for cooling 10 the engines in motor vehicles that are provided with explosion or internal combustion engines, and it has reference more particularly to an air-cooling system embodying a detachable air-cooled head adapted to be substituted for the usual water-cooled engine 15 head provided in certain types of engines of this class.

The primary object of the present invention is to provide air-cooling means whereby 20 the natural air-currents to which the engine is subjected during the motion of the vehicle, or artificially created air-currents, or both, are utilized as a cooling medium. Said means to take the place of water-cooling systems at present more or less universally used. 25 Engines provided with the improved cooling means are better adapted for motorcycles, automobiles, and similar vehicles than engines provided with the means heretofore employed, as they are more efficient and less 30 troublesome.

Another object of the invention is the provision of means for combined air and oil 35 cooling, the engine head being air cooled while the cylinders are oil cooled.

A further object of the invention is the provision of air and oil cooling means that can readily be substituted for the water cooling systems with but little change in the 40 general design of the engine.

A further object is to provide means for the purpose set forth, that is simple and durable in construction, and economical to install and maintain.

With these and other apparent objects in view, the invention consists of a detachable air-cooled engine head adapted to substitution for the usual water-cooled head, a funnel or megaphone shaped member 50 being attached to the side water inlet opening in the cylinder block casting, and extending forward to the front of the engine hood. The funnel member takes the

air-currents created by the fan and by the motion of the vehicle, and causes their circulation through the lower part of what was formerly the cylinder water jacket. Suitable outlets are provided in the air-cooled head to permit the escape of the hot air from the old water jacket, which remains 60 an integral part of the cylinder block casting.

Further construction, combination and arrangement of the elements embodied in the invention will be fully described in the specification and pointed out definitely in the 65 appended claims, reference being had to the accompanying drawings, in which similar characters of reference designate corresponding parts.

As the standard engine employed in the 70 Ford automobile is well known, and as this improvement is appropriate to that engine, it will be used for purposes of explanation, therefore this specification has reference to an embodiment of the invention adaptable 75 particularly to the Ford type of engine, it will however be understood that the scope of the invention will admit of its application to other engines of the explosion type, which are provided with detachable heads.

In the drawings Figure 1 is an outline elevation of a Ford engine equipped with the improved air-cooling means.

Fig. 2 is a fragmentary view of the side of the engine opposite to that shown in 85 Fig. 1.

Fig. 3 is a fragmentary front view.

Fig. 4 is a top plan view, and Fig. 5 an underside view of the detachable head.

Fig. 6 is a side elevation of said head, and 90 Fig. 7 is a section on line 7—7 of Fig. 5.

Fig. 8 is an outline elevation showing the connections for a combined air and oil cooling system, and Fig. 9 is a plan view.

In engines of the type to which the present 95 invention is applicable, the cylinder block casting 1 is provided with a water jacket, the cylinder head is also jacketed. When water cooled, the water from the lower radiator tank is conducted into the cylinder block 100 water jacket through a pipe connected with said block at 1^a, and by thermo-siphon circulation passes from the cylinder block, through the head to the upper radiator tank, and from there through the cooling members, back to the lower radiator tank.

This invention provides for using the old water jacketed cylinder block, attaching thereto at 1^a a funnel shaped member 2. The member 2 extends forward to the radiator casing 3. The radiator tanks and other members ordinarily contained in the radiator case are preferably eliminated and a screen of more or less extensive open mesh is substituted therefor, thus allowing free access of air from the front of the vehicle. The air-currents created by the motion of the vehicle, and by the fan 4 are caught by the funnel member 2 and circulated through the jacket in the cylinder block. Outlets 5 are provided in the detachable head 6 for the escape of the hot air from the lower jacket, which is driven out by the incoming cold air currents.

The exterior of the detachable head is provided with a series of ridges or flanges 7, preferably cast integral therewith and in "herring-bone" arrangement, as shown in Fig. 4, and deflecting plates 8 are cast on the inside of the head. The members 7 radiate the cool air taken in from the front of the vehicle and confined by a hood 9 over the engine head. The hood is shown in section in Fig. 1. The plates 8 cause the cold air coming into the cylinders through the intake valves to be deflected across the top of the exhaust valves.

The detachable head is designed to correspond to the contour of the cylinder block and gasket, and is provided with suitable bosses 10 having bolt holes therein that register with the bolt holes in said gasket and cylinder block. Provision is also made in the head or spark-plugs, as shown at 11.

In certain types of engines, notably the Ford, core holes 12 are provided in the cylinder block, and when water-cooled these holes are plugged. When the improved air-cooling means are employed the plugs are removed and the hot air allowed to escape through the holes from the chamber. In some instances it is desirable to connect the carbureter intake pipe with one or more of said core holes and thus take the hot air to the carbureter and also assist the cooling by the incoming air circulating through the jacket in the engine block and openings in the air cooled head.

The present invention is primarily intended to be used particularly in freezing weather to overcome the annoyance incidental to freezing of radiators and water jackets, however if it is desired to employ the air-cooled head perpetually, an oil tank 15, Fig. 8, can be added, said tank being suitably connected to the inlet 1^a of the jacket in the cylinder block, as shown at 17, and connections 16 made through the air-cooled head from the outlet 5 which opens into the jacket of the cylinder block, thus 65 the head of the engine is air-cooled while

that part of the engine cast integral with the cylinders is cooled by thermo-siphon circulation of oil.

Having now described a certain embodiment of my invention, what I claim and desire to secure by Letters Patent is.

1. Means for cooling internal combustion engines, comprising a jacketed cylinder block, a detachable head for said block, said head having deflecting members on the interior thereof, ports through said head connected with the jacket in the cylinder block, and means for circulating air through the cylinder block and head. 75

2. Means for air cooling internal combustion engines, comprising a jacketed cylinder block, a detachable head for said block, said head having deflecting members on the interior thereof, ports through said head connected with the jacket in the cylinder block, air cooling flanges on said head, connections with the cylinder block jacket and connecting ports in the head providing thermo-siphon circulation through 85 said cylinder block and head. 90

3. In an air-cooled engine, a detachable cylinder head adaptable to an air-jacketed cylinder block, said head being provided with ports that connect with the air chamber in the cylinder block, and having cooling flanges on the exterior and deflecting plates on the interior thereof. 95

4. Means for air-cooling engines, comprising a cylinder block having a jacket that provides an air-chamber around the cylinders, an exterior air-conductor connected with said air-chamber on one side of the block and openings from said chamber on the opposite side thereof, a detachable head for said block, said head being provided with ports that extend therethrough and connect with the air-chamber in the cylinder block, cooling flanges on the exterior and deflecting plates on the interior of said head, and a hood over the head for receiving exterior air currents whereby said head is cooled. 100 105 110

5. Means for air-cooling engines, comprising a cylinder block having a jacket that provides an air-chamber around the cylinders, an exterior air-conductor connected with said air-chamber on one side of the block, and openings from said chamber on the opposite side thereof adapted for connection with the engine carbureter, a detachable head for said block, said head being provided with ports that extend therethrough and connect with the air-chamber in the cylinder block, and having deflecting members on the interior thereof. 115 120

6. Means for converting a water-cooled engine provided with a detachable head, to an air-cooled engine, comprising an air-cooled head adapted to substitution for the water-cooled head, said air-cooled head having cooling flanges on the exterior and deflect- 125 130

ing members on the interior thereof and ports therethrough that connect with the jacket provided in the cylinder block, and an air conductor connected with said water-jacket in place of the water supply pipe.

7. In an air-cooled engine, a detachable cylinder head adaptable to an air-jacketed

cylinder block, said head being provided with ports that connect with the air chamber in the cylinder block, and having deflecting members on the interior thereof.

10
In testimony whereof I affix my signature.

COROL R. BAKER.
